No. 37,155.

Patented October 4, 1904.

UNITED STATES PATENT OFFICE.

NELSON RUSH SNIDER, OF ASHER, OKLAHOMA TERRITORY.

DESIGN FOR A BADGE.

SPECIFICATION forming part of Design No. 37,155, dated October 4, 1904.

Application filed August 25, 1904. Serial No. 222,133. Term of patent 7 years.

To all whom it may concern:

Be it known that I, NELSON RUSH SNIDER, a citizen of the United States, residing at Asher, in the county of Pottawatomie, Oklahoma Territory, have invented a new, original, and ornamental Design for a Badge, of which the following is a specification.

My design for a badge is clearly illustrated in the accompanying drawings, in which I have shown a plan view of the same.

What I claim as new, and desire to secure by Letters Patent, is—

The ornamental design for a badge as shown.

NELSON RUSH SNIDER.
